MOUNTING FOR FIXED RESISTORS

Erwin R. Stockle, Milwaukee, Wis., assignor to
 Central Radio Laboratories, Milwaukee, Wis.,
 a corporation of Wisconsin

Application May 13, 1932, Serial No. 611,154

3 Claims. (Cl. 201—63)

This invention relates to an improvement in mountings for fixed resistors used in radio receiving sets.

One of the objects of the present invention is 5 to provide a mounting of this character of simple and compact construction susceptible of easy and economical production from materials and by means of facilities ordinarily available and which provides a rigid support for one or more fixed 10 resistors and maintains the resistors in spaced relation to each other and in spaced relation to the support upon which they are mounted.

Another object is to provide a mounting having these advantages and which provides a simple 15 and effective means for securely fastening the resistors and particularly resistors of the cylindrical rod type to the mounting and this in such manner that although the resistors are firmly held their terminals are conveniently accessible for the purpose of soldering wires thereto.

20 Other objects and advantages reside in certain novel features of the construction, arrangement and combination of parts which will be herein-after more fully described and particularly pointed out in the appended claims, reference being 25 had to the accompanying drawing, forming a part of this specification, and in which:

Figure 1 is a perspective view showing a mounting embodying the present invention prior to the 30 securing of the resistors thereon;

Figure 2 is a view in top plan showing the 35 mounting of Figure 1 with the resistors assembled therewith and secured in position; and

Figures 3, 4 and 5 are views in vertical section taken on lines 3—3, 4—4 and 5—5, respectively, 40 of Figure 2.

Referring to the drawing, it will be seen that the mounting embodying the present invention is generally of channel shaped formation, being 45 constructed of a single piece of sheet metal bent or shaped to provide a flat bottom or body portion 1 and side flanges 2. The side flanges 2 are formed with curved seats 3 located between the members of pairs of holding fingers or projections 4. There is a notch-like space or slot 5 between each pair of holding fingers. The seats 3 and holding fingers 4 are transversely alined, the seats providing in effect a cradle for receiving the cylindrical body portion of a resistor R. After the resistors are positioned in the cradle 50 afforded by the seats 3, the fingers or projections 4 are bent around and into snug gripping engagement with the resistors, as will be understood from Figures 2 and 4. Any suitable tool may be used to form over the fingers and cause them to

embrace the resistors securely and hold them in position.

The body portion 1 is provided with extensions 8 and 9 at its ends, which extensions are notched or apertured as at 8' and 9' to provide a means adapted for coaction with screws or other fasteners F for the purpose of securing the mounting in position. In Figures 3 and 4 the mounting is illustrated as fastened by the screws F to a portion of the radio cabinet designated at C. 10

It will be noticed that the cradles thus provided on the mounting engage the intermediate portions of the resistors and that the end portions of the resistors and their terminals T project outwardly beyond the sides of the mounting and are conveniently accessible for soldering wires thereto. 15

The resistors may be formed with integral insulating jackets, but if such insulating jackets are not provided as part of the resistor then they are enveloped in a piece of sheet fiber or other suitable insulating jacket J. In this manner, the resistors are electrically insulated from the metal frame or mounting and from one another, and they are securely held in spaced relation, both 20 with respect to themselves and with respect to their support. It is apparent that any desired number of fixed resistors may be mounted in such a support by providing the necessary number of transverse cradles and holding fingers or 25 projections in the channel frame. 30

One of the important objects of the present invention is the provision of a resistor mounting having spaced metal portions provided with alined seats and equipped adjacent the seats with holding fingers adapted to be bent into securing engagement with the resistors. Obviously, it is not essential that the metal portions be in the form of strips or be connected by a bottom plate to assume a channel formation. These metal 40 portions may be in the form of circular plates with the seats and fingers on the periphery of the plates, with the plates horizontally disposed and connected at their centers by means of a post or other suitable connecting member. 45

While I have shown and described one type of construction embodying the present invention, it is to be understood that this has been selected merely for the purpose of illustration 50 and example and that various changes in the size, shape, construction and arrangement of the parts may be made without departing from the spirit of the invention or the scope of the subjoined claims. 55

The invention claimed is:

1. A mounting frame for fixed resistors constructed of a single piece of metal and comprising a formed channel having a flat bottom and side flanges of single thickness, said side flanges having aligned slots and being provided with pairs of projections between said slots, said projections forming spaced transverse cradles adapted to receive said resistors and support the same intermediate their ends, the members of each pair of projections being of narrow width and having their upper portions extended toward each other and into embracing engagement with said resistors to securely hold the latter on said frame and in spaced relation to each other and to the base on which said frame is mounted.
2. A support for a group of fixed resistors comprising a channel, said channel having means whereby it may be fastened in position on a suitable support, said channel having transversely aligned slots in its sides and also having pairs of projections on said sides between said slots, transversely aligned pairs of said projections forming

cradles adapted to receive said resistors, said projections being extended around and into embracing engagement with said resistors to secure the latter in position.

3. A support for a group of fixed resistors comprising a channel constructed of a single piece of metal and having openings in the bottom thereof for receiving fastening devices whereby said support may be secured in position, the sides of said channel having transversely aligned slots and also having pairs of projections between said slots, transversely aligned pairs of said projections forming cradles adapted to receive said resistors, said projections being adapted to have securing engagement with said resistors to hold them in position in said cradles and insulation interposed between said resistors and said channel and its projections whereby to preclude electrical contact between said resistors and said support and the structure on which the support is mounted.
